UNITED STATES PATENT OFFICE.

CHARLES HUBERT LEE, OF LOS ANGELES, CALIFORNIA, ASSIGNOR OF ONE-HALF TO LEIGH J. MONSON, OF FARGO, NORTH DAKOTA.

DESIGN FOR A RING.

Application filed May 21, 1928. Serial No. 26,778. Term of patent 7 years.

To all whom it may concern:

Be it known that I, CHARLES HUBERT LEE, a citizen of Canada, residing at Los Angeles, in the county of Los Angeles and State of California, have invented a new, original, and ornamental Design for a Ring, of which the following is a specification, reference being had to the accompanying drawing, forming a part thereof.

I claim:

The ornamental design for a ring, as shown.

Signed at Los Angeles, in the county of Los Angeles, and State of California, this 12th day of May, 1928.

CHARLES HUBERT LEE.

CERTIFICATE OF CORRECTION.

Design No. 76,691.

Granted October 23, 1928, to

CHARLES HUBERT LEE.

It is hereby certified that the above numbered patent was erroneously issued to the inventor said "Lee and Leigh J. Monson", as joint owners of said invention, whereas said patent should have been issued to the inventor said "Charles Hubert Lee", as sole owner of said invention; and that the said Letters Patent should be read with this correction therein that the same may conform to the record of the case in the Patent Office.

Signed and sealed this 15th day of January, A. D. 1929.

M. J. Moore,
Acting Commissioner of Patents.
